UNITED STATES PATENT OFFICE.

MORRIS WOODHULL, OF DAYTON, OHIO.

HINGED DOOR FOR PIANO-BOX BUGGIES.

SPECIFICATION forming part of Letters Patent No. 678,710, dated July 16, 1901.

Application filed April 25, 1901. Serial No. 57,390. (No model.)

To all whom it may concern:

Be it known that I, MORRIS WOODHULL, a citizen of the United States, residing at Dayton, in the county of Montgomery and State 5 of Ohio, have invented certain new and useful Improvements in Hinged Doors for Piano-Box Buggies, of which the following is a specification.

My invention relates to vehicles, and more 10 especially to that class of vehicles known as "piano-box buggies."

Owing to the short distance between the top and the high sides of the box in buggies of this character the difficulty of getting in 15 and out is well known; and the object of my invention is to overcome this by providing a door that will be strong and substantial and which can be opened and closed without interfering with the adjacent step and wheels 20 of the buggy. I attain these objects by the constructions and combinations hereinafter described, and shown in the accompanying drawings, in which—

Figure 1 is a side elevation of a portion of 25 a buggy embodying my device, showing the door closed; and Fig. 2 is the same with the door open. Fig. 3 is an interior perspective view of a portion of the box-bed, showing the door partly open. Fig. 4 is a plan view of 30 the frame of my device, and Fig. 5 is a side view of an arm of the frame with the bearings for same shown in section.

Like parts are represented by similar letters of reference in the several views.

In constructing my device I employ the 35 angularly-extending arms *a*, pivoted at one end in the bosses *b'* of the plate *b*, which is attached to the bottom of the bed *c*, the collar or offset *a'* on the arm *a* seating itself 40 against the boss *b'* and the arm extending through said boss and attached in place by the nut *b*³, the other end of said arm extending into the socket *d'* of the frame *d*, which is attached to the door *e*, said arm being pivoted with the offset or collar *a*², which bears 45 against the enlarged end *d*² of the socket *d'*, said arm extending through said socket and being attached in place by the nut *e*³. Said frame is further provided with the stop *e*⁴ to

contact with the side of the box when the 50 door is closed. The door *e* is further provided with the latches *e*⁵ to hold the door in place when closed. The door-opening is provided at each side with the plates *c'* and at the bottom with the pieces *c*⁴, attached to the said 55 box to strengthen the sides of the box and at the same time provide a stop for the door when closed. The side plates are beveled at *c*², so that the latches *e*⁵ when fastened over same will bind the door in place and prevent 60 any rattle, and the block *c*³ strengthens the bottom of the bed where the plate *b* is attached.

It will be seen that by means of the angularly-extending arms pivoted at their respective ends to the bed and the door, the door may be opened and closed without interfering with the step *f*, or the adjacent wheel of the vehicle; the door operating in a side-stepping instead of the usual swinging movement, and the curve of the arm permits it to pass the arm of the step so that the door may be thrown from its closed to open position, and when side open occupies a position adjacent to the doorway and parallel to the adjacent side of the box, where it is out of the way and presents the best appearance.

Having thus described my invention, I claim—

The combination with the box-bed of a vehicle having an opening in the side thereof, of a door for said opening having vertically-extending sockets on each side of its medial line, angularly-extending arms pivoted at one end to the under side of said bed and at the 85 other journaled in said sockets and adapted to carry said door in its upright position, whereby said door may be opened and closed, by a side-stepping movement, without interfering with the adjacent wheel of the vehicle, substantially as specified.

In testimony whereof I have hereunto set my hand this 18th day of April, A. D. 1901.

MORRIS WOODHULL.
